SUPPORT FOR VENETIAN BLINDS

Guy W. Kirsch, Sturgis, Mich., assignor to
Kirsch Company, Sturgis, Mich.

Application April 29, 1935, Serial No. 18,839

11 Claims. (Cl. 156—17)

This invention relates to Venetian blinds, particularly to Venetian blind constructions for use in connection with steel sash windows. In ordinary steel sash window construction, the windows swing outwardly and the screens for use in the summer time are placed inside the window. In such a construction, it is desirable to have a Venetian blind that can be easily removed to permit removal of the screens for washing the inside of the windows or the like or to permit access to the windows for any other reason. It is essential that the bracket which supports the Venetian blind be of a nature that will not interfere with the removal of the screen.

The objects of the present invention are:

First, to provide a Venetian blind construction in which the blind may be removed as a unit and in which the brackets may be partially removed to permit access to the screen for removal.

Second, to provide a bracket and support for a Venetian blind to be used in casement window construction, which support is easily installed on a steel sash window construction and which is adjustable to permit proper positioning of the blind.

Third, to produce a means for supporting a Venetian blind that is easily and quickly manipulated to release the blind for removal, but which holds the blind firmly and which is not objectionable in appearance and appears to be merely a continuation of the header of the blind.

Fourth, to produce a supporting means for a Venetian blind, which holds the blind firmly but is easily removed, and which makes possible liberal allowances for errors in measuring of windows preparatory to installing Venetian blinds.

Further objects and advantages pertaining to detail and economies of construction and operation will appear from the description to follow.

A preferred embodiment of my invention is illustrated in the accompanying drawing, in which:

Fig. 1 is a perspective view of my improved bracket for supporting Venetian blinds on a steel sash window.

Fig. 2 is a sectional plan view of my device taken on lines 2—2 of Figs. 3 and 4, showing the blind header supported in position.

Fig. 3 is a sectional view taken on line 3—3 of Fig. 2.

Fig. 4 is a sectional view taken on line 4—4 of Fig. 2, showing details of the supporting means.

Fig. 5 is a sectional plan view showing my con-

struction in position on a steel casement window having an inside screen.

In the drawing, 1 is the steel frame of a steel casement window of ordinary construction which has outwardly swinging windows 2 with hinges 3. The window is shown installed in a well 4 as is usual practice with such windows.

5 is a sheet metal bracket having a flange 6 at the end thereof abutting against the frame 1 of the window. The flange is apertured as at 7 for the insertion of screws 8 which are inserted in suitable tapped holes in the frame 1.

The aperture 7 extends into the flange 6 and also into the bracket 5 as is best shown in Figs. 2 and 5, to permit easy insertion of the bracket 10 which is clamped in place with the screws.

The bracket 5 is provided with parallel horizontal ridges 9 struck up in the metal. These ridges are apertured as at 10 for the passage of bolts 11 which are provided with nuts 12 as illustrated in Fig. 3.

13 is a sliding member adapted to be fastened to the bracket 5. The sliding member 13 is formed of sheet metal and has struck up portions 14 forming registering slide ways to register with the struck up ridges 9.

The struck up portions 14 are slotted as at 15 for the passage of the bolts 11 to permit the clamping of the sliding member 13 to the bracket 5 and to permit adjustment to or away from the window.

The outer end 16 of the sliding member is offset as shown in Fig. 2 to provide clearance. Located centrally of the offset portion 16 is a keyhole slot 17 having its narrow end 18 extending inwardly toward the window in a horizontal direction. At the front edge of the portion 16 is formed an upwardly facing hook 19 substantially on a level with the portion 18 of the key-hole slot 17.

20 is a sheet metal socket member comprising a bottom or bearing plate 21 and having a rear flange 22 serving as a stop, a bottom flange 23 serving as a support for a header bar, and a top flange 24 serving to form the top of an open front socket member into which a header bar 25 may be slid.

Extending from the rear of the bearing plate 21 are headed studs 26 and 27 spaced from one another and in such relation that when the headed stud 26 is inserted in the keyhole slot 17 and moved to the rear thereof the headed stud 27 engages in the hook 19 on the front of the sliding member 13.

The header bar in the particular construction 55

shown is preferably formed of sheet metal to produce a channel. The sheet metal is of such gauge that the metal may be slightly flexed and the bar is of a size to fit in the socket member 20, 5 with the open side upwardly as shown in Fig. 4.

To hold the channel header bar 25 in position, I provide a member 28. This locking member 28 consists of a metal plate 29 which is adapted to engage the exposed surface of the channeled header 25 to hold it in the socket 20. Extending from this plate on one side thereof is a hook 30 having its point facing toward the plate 29. The hook extends rearwardly of the plate 29 sufficiently to engage a headed stud 31 extending 15 from the bearing plate 21 of the socket 20.

When the plate 29 is lying against the front of the channeled header 25, the point of the hook extends towards the plate 29 a sufficient length to hold the locking member 28 in position, but 20 the point of the hook is of such length that pressure exerted on the plate 29 will flex the channel header 25 inwardly sufficiently to permit the locking element 28 to be removed by sliding it vertically along the front of the header bar 25, 25 permitting the point 32 of the hook 30 to clear the headed stud 31.

In order to facilitate sliding the locking member 28, I provide a raised portion 33 thereon and provide one end of the plate 29 be turned up as at 30 34.

In installing Venetian blinds, many times the measurements are made incorrectly and it is desirable to have the sockets 20 of such size that if a short header bar is inserted it will be properly supported. To this end I provide that the flanges 22, 23, and 24 be of sufficient length to satisfactorily support a short header bar, and I provide that the front plate 29 of the locking element 28 be of such width that it will fill in any 40 gap left between the ends of the header bar and the bearing plates 21 of the sockets 20.

The bearing plate 29 is of a length substantially the same as the height of the channel 25, so that even if the header bar 25 is considerably shorter 45 than would fit the opening, no unsightly gaps are left exposed.

The provision of this particular locking element makes the removal of the header bar a simple matter and presents at all times a neat appearance.

In Fig. 5, I have shown a screen 35 installed on the inside of the window 2. The bracket 5 extends beyond the screen and the sliding member 13 which, as illustrated in Fig. 1, positions the 55 header bar of the Venetian blind inside of the screen.

If it is desired to have access to the screen, it is a simple matter to remove the locking member 28, remove the Venetian blind by removing the 60 header bar 25, and then remove the socket 20, leaving a clear space for the opening or removal of the screen.

In the drawing, I have not illustrated a Venetian blind, but have illustrated only the header 65 bar 25. It will be appreciated that the Venetian blind is of the usual slat construction hanging from the header bar 25 and so arranged that the blind is a complete unit. The details of the blind are unimportant in so far as this invention is concerned and have not been illustrated in detail.

I have shown a preferred embodiment of my invention and wish to claim the same specifically and also broadly as pointed out in the appended claims.

75 Having thus described my invention, what I

claim as new and desire to secure by Letters Patent is:

1. In a Venetian blind construction for use on sash windows to permit easy removal of the blind for access to screens or the like on the inside of the windows including a header bar comprising a sheet metal channel having its open side upwardly facing and formed of metal of a gauge to permit flexing of the sides of the channel inwardly, a bracket, a sliding member thereon, means to fasten said sliding member on said bracket, an offset portion on said sliding member, said offset portion having a keyhole slot, the narrow portion of said slot extending rearwardly and said offset portion having an upwardly facing hook at the forward end thereof, a header engaging socket member having an open front to slidably receive one end of said header, comprising a sheet metal bearing plate having a bottom flange forming a horizontal seat for said header and a rear flange forming a stop therefor, a pair of headed studs extending from the back of said bearing plate and spaced from one another, one stud being positioned to be inserted in said rearwardly facing keyhole slot and to be moved rearwardly thereof and the other headed stud being so positioned that when said first mentioned stud is at the rear of said keyhole slot said second stud engages in the hook on the front edge of said sliding member, said bearing plate having a third headed stud extending from the front side thereof, and a locking element comprising a metal plate for engaging the front of the header and having extended from one side thereof a hook having its point faced toward said locking plate, said hook being of a length to engage said headed stud on the front of said bearing plate between its head and said bearing plate when the header is in position on said horizontal seat and against said stop and when the plate of said locking element is against the front face of the header, the point of the hook being of such length that a flexing of the side of the header bar will permit the hook to be disengaged by a sliding of the plate vertically along the end of the header.

2. In a Venetian blind construction including a header bar comprising a sheet metal channel having its open side upwardly facing and formed of metal of a gauge to permit flexing of the sides of the channel inwardly, an open front socket member to slidably receive one end of said header, comprising a sheet metal bearing plate having a bottom flange forming a horizontal seat for said header and a rear flange forming a stop therefor, a headed stud extending from said bearing plate, and a locking element comprising a metal locking plate for engaging the front of the header and having its outer side ribbed to facilitate removal thereof by frictional engagement and having extended from one side thereof a hook having its point facing toward the plate, said hook being of a length to engage said headed stud between its head and said bearing plate when the header is in position on said horizontal seat and against said stop and when the plate of said locking element is against the front face of the header, the point of the hook being of such length that a flexing of the side of the header bar will permit the hook to be disengaged by a sliding of the plate vertically along the end of the header.

3. In a Venetian blind construction including a header bar comprising a sheet metal channel having its open side upwardly facing and formed

of metal of a gauge to permit flexing of the sides of the channel inwardly, an open front socket member to slidably receive one end of said header, comprising a sheet metal bearing plate having a bottom flange forming a horizontal seat for said header and a rear flange forming a stop therefor, a headed stud extending from said bearing plate, and a locking element comprising a metal locking plate for engaging the front of the header and having extended from one side thereof a hook having its point facing toward the plate, said hook being of a length to engage said headed stud between its head and said socket when the header is in position on said horizontal seat and against said stop and when the plate of said locking element is against the front face of the header, the point of the hook being of such length that a flexing of the side of the header bar will permit the hook to be disengaged by a sliding of the plate vertically along the end of the header.

4. In a Venetian blind construction including a header bar comprising a sheet metal channel having its open side upwardly facing and formed of metal of a gauge to permit flexing of the sides of the channel inwardly, an open front socket member to slidably receive one end of said header and having a horizontal seat for said header and a rear stop therefor, a headed stud extending from said socket member, and a locking element comprising a metal locking plate for engaging the front of the header and having extended from one side thereof a hook having its point facing toward the plate, said hook being of a length to engage said headed stud between its head and said socket when the header is in position on said horizontal seat and against said stop and when the plate of said locking element is against the front face of the header, the point of the hook being of such length that a flexing of the side of the header bar will permit the hook to be disengaged by a sliding of the plate vertically along the end of the header.

5. In a Venetian blind construction, the combination of a header bar comprising a sheet metal channel having its open side upwardly facing and formed of metal of a gauge to permit flexing of the sides of the channel inwardly, an open front socket member to slidably receive one end of said header and having a horizontal seat for said header and a rear stop therefor, a stud extending from said socket member, and a locking element comprising a metal locking plate for engaging the front of the header and having engaging means thereon to engage said stud when the header is in position on said horizontal seat and against said rear stop, said engaging means being disengageable by flexing of the header and movement of said locking element.

6. In a Venetian blind construction for use on sash windows to permit easy removal of the blind for access to screens or the like on the inside of the windows including a header, a bracket having a ridge therealong, a sliding member having a ridge registering with said first mentioned ridge and slotted for the passage of a bolt, a bolt extending through said ridges and through the slot of said sliding member, an offset portion on said sliding member, said offset portion having a key-hole slot with its narrow portion extending rearwardly and having an upwardly facing hook at the forward end thereof, a header engaging socket member comprising a bearing plate having upturned flanges, and a pair of headed studs extending from the rear of said bearing plate and

spaced from one another, one stud being positioned to be inserted in said rearwardly facing keyhole slot and to be moved rearwardly thereof and the other headed stud being so positioned that when said first mentioned stud is at the rear of said keyhole slot said second stud engages in the hook on the front edge of said sliding member.

7. In a Venetian blind construction for use on sash windows to permit easy removal of the blind for access to screens or the like on the inside of the windows including a header, a bracket, a sliding member, means to fasten said sliding member on said bracket, an offset portion on said sliding member, said offset portion having a key-hole slot with its narrow portion extending rearwardly and having an upwardly facing hook at the forward end thereof, a header engaging socket member comprising a bearing plate having upturned flanges, and a pair of headed studs extending from the rear of said bearing plate and spaced from one another, one stud being positioned to be inserted in said rearwardly facing keyhole slot and to be moved rearwardly thereof and the other headed stud being so positioned that when said first mentioned stud is at the rear of said keyhole slot said second stud engages in the hook on the front edge of said sliding member.

8. In a Venetian blind construction for use on sash windows to permit easy removal of the blind for access to screens or the like on the inside of the windows, including a header, a bracket, a sliding member, means to fasten said sliding member on said bracket, an offset portion on said sliding member, said offset portion having a key-hole slot with its narrow portion extending rearwardly and having an upwardly facing hook at the forward end thereof, a header engaging socket member, and a pair of headed studs extending from the rear of the socket and spaced from one another, one stud being positioned to be inserted in said rearwardly facing keyhole slot and to be moved rearwardly thereof and the other headed stud being so positioned that when said first mentioned stud is at the rear of said keyhole slot said second stud engages in the hook on the front edge of said sliding member.

9. In a Venetian blind construction for use on sash windows to permit easy removal of the blind for access to screens or the like on the inside of the windows, including a header, a bracket, a sliding member, means to fasten said sliding member on said bracket, a header engaging socket member, and means for detachably fastening said socket member to said sliding member.

10. In a Venetian blind construction for use on windows to permit easy removal of the blind for access to screens or the like on the inside of the windows including a header, a bracket, a keyhole slot in said bracket with its narrow portion extending rearwardly and having an upwardly facing hook at the forward end thereof, a header engaging socket member comprising a bearing plate having upturned flanges, and a pair of headed studs extending from the back of said bearing plate and spaced from one another, one stud being positioned to be inserted in said rearwardly facing keyhole slot and to be moved rearwardly thereof and the other headed stud being so positioned that when said first mentioned stud is at the rear of said keyhole slot said second stud engages in the hook on the front edge of said sliding member.

11. In a Venetian blind construction for use on

windows to permit easy removal of the blind for access to screens or the like on the inside of the windows including a header, a bracket, a key-hole slot in said bracket with its narrow portion extending rearwardly and having an upwardly facing hook at the forward end thereof, a header engaging socket member, and a pair of headed studs extending from the back of the socket and

spaced from one another, one stud being positioned to be inserted in said rearwardly facing keyhole slot and to be moved rearwardly thereof and the other headed stud being so positioned that when said first mentioned stud is at the rear of said keyhole slot said second stud engages in the hook on the front edge of said sliding member. 5

GUY W. KIRSCH.
